APPARATUS FOR GROOVING ROLLS

Virgil S. Jackson, Weirton, W. Va., assignor to
 National Steel Corporation, a corporation of
 Delaware

Application April 29, 1948, Serial No. 23,885

1 Claim. (Cl. 90—56)

1

The present invention relates to improvements in apparatus for cutting grooves in rolling mill rolls and more particularly relates to apparatus for cutting a plurality of parallel longitudinal grooves in the peripheral surface of blooming mill rolls. This operation is commonly called "ragging."

When rolling a steel ingot to form a bloom, billet, slab, bar, or the like, the blooming rolls receiving the ingot are often provided with parallel longitudinal grooves arranged around the periphery of the roll. These spaced, relatively shallow grooves are provided to increase the bite of the blooming rolls and to aid in pulling or drawing the ingot into the rolls. These blooming mill rolls are very large and heavy and weigh a number of tons. It has been the practice to place the roll on a suitable machine by means of a crane and to then cut or machine one or a few grooves in the roll, depending upon the capacity of the cutting machine. The crane, or some other powerful lifting device, is then used to turn the heavy roll sufficiently about its longitudinal axis to permit the cutting of an additional groove or grooves in the peripheral surface. These steps are repeated until the entire periphery of the roll has received the desired number of grooves. This procedure is very slow and laborious and requires an excessive amount of time. It is common practice to take about 8 to 10 hours to cut the grooves in a blooming mill roll. In addition, it is difficult to accurately position the roll for properly cutting these grooves and if these grooves are not cut correctly, the roll will not function properly.

Accordingly, it is an object of the present invention to provide an improved apparatus for ragging blooming mill rolls.

Another object of the present invention is to provide an improved apparatus for cutting grooves more accurately in blooming mill rolls in less time than heretofore required.

Another object of the present invention is to provide an improved apparatus which can be readily positioned on a cutting machine for turning a blooming mill roll to accurately position the roll for cutting longitudinal grooves in its peripheral surface and which can be readily removed from the cutting machine.

A further object of the present invention is to provide an improved power-actuated portable mechanism for indexing a blooming mill roll to accurately and successively positioning the roll for successively cutting a series of parallel grooves in the peripheral surface of the roll.

2

The present invention provides an improved power-actuated mechanism which can be readily positioned on a suitable cutting machine, such as a planer, for intermittently turning a blooming mill roll about its longitudinal axis. The mechanism is portable so that it can be readily moved and positioned and it includes a rotatably supported member having its center portion shaped to fit over the wobbler of the blooming roll. The wobbler engaging member is connected through a gear train to a motor for turning the roll to position the roll for the successive cuts. When using this mechanism, it is possible to reduce the time required for cutting the grooves in a blooming mill roll from the usual 8 to 10 hours to 3 to 1 1/4 hours, or less.

These and other objects and advantages will become more apparent when considering the following detailed description, taken with the accompanying drawings, in which:

Figure 1 is a side elevational view of apparatus embodying the principles of the present invention;

Figure 2 is a plan view, partially in section, of the apparatus of Figure 1; and

Figure 3 is an enlarged sectional view, taken along line 3—3 of Figure 1, in which the blooming mill roll has been omitted to more clearly show the structures of the apparatus.

Referring more particularly to the drawings, a blooming roll 10 includes a relatively large, work engaging center portion 11 adapted to roll a steel body, such as an ingot, and reduce it in cross-sectional size to form a bloom. The blooming mill roll 10 also includes roll necks 12 which are adapted to be rotatably mounted in the bearings of a roll mill stand, not shown, when in use. At least at one end of the roll 10 there is a wobbler 13 which is an irregularly shaped portion adapted to fit into a correspondingly shaped opening in a drive gear, not shown. When cutting grooves in the blooming mill roll, the roll is transferred by any suitable means, such as a crane, to the mechanism for cutting the grooves. As is shown in the drawings, the roll 10 is rotatably supported in a pair of V blocks 14 and 15 mounted on a bed 16 of a planer. The bed 16 is slidably supported for movement back and forth along the ways 17 of the planer or other cutting machine. The direction of movement of bed 16 and the roll 10 is parallel with the longitudinal axis 18 of the roll. A cutting tool 19 is suitably supported on a support 20 in position for cutting a groove 21 in the peripheral surface of the roll 10 when the roll is

moved longitudinally to effect relative movement of the tool 19 along the surface of the roll.

An indexing mechanism 23 for turning the roll 10 about its longitudinal axis 15 is removably mounted on the planer bed 16. The mechanism 23 includes a supporting or base plate 24 on which are mounted a pair of spaced side plates 25. The plates 25 are connected and held together by a plurality of bolts 26 and are spaced apart by the spacers 27, one of which is provided for each bolt 26. A cover 29 extends about the side plates 25 for preventing the entrance of dirt and damage to the mechanism. The mechanism 23 includes a relatively large wrench member 30 having an outer ring gear 32 extending entirely around its periphery and between the plates 25 and includes spaced, longitudinally extending bearing shoulders 33 disposed on opposite sides of the ring gear 32 which rotatably support the wrench member 30 in the side plates 25. The wrench member 30 is also provided with a central opening 34 shaped to fit the wobbler 13 so that when the member 30 is rotated, as hereinafter described, the roll is also rotated.

The power-actuated driving means for rotating member 30 and roll 10 includes a motor 35 mounted on channels 36 and connected to a gear reducer 37 for driving gear 38 which meshes with a gear 39 mounted on and connected to a short shaft 40. A second gear 41 is also mounted on and connected to the shaft 40 in position to engage the ring gear 32. The shaft 40 is rotatably mounted in the side plates 25. Rotation of motor 35 rotates gears 38, 39, and 41 to turn the member 30 and the roll 10. Bearing metal is provided at 42 to form bearing surfaces in side plates 25 for the shoulders 33 of wrench member 30 to reduce friction and the force required to turn the roll 10. This bearing metal may be separate rings or may be deposited by welding.

The planer bed 16 may be moved back and forth along the ways 17 in any suitable manner. As shown in the drawings, a rack 44 is mounted on the under side of bed 16. A reversible, power-driven gear means, not shown, meshing with rack 44, and of the type generally used for moving large planer beds, may be provided for moving the bed 16.

The mechanism 23 includes a plate 45 which covers part of gears 39. This cover 45 may be extended laterally to cover and protect completely the gears 39 and 38. A member 46 is also fastened to the mechanism and member 46 has an opening 47 in its upper end for receiving the hook of a crane, not shown, so that the mechanism can be readily removed from or placed in position on the bed 16.

When the blooming mill roll 10 is to be grooved, the V blocks 14 and 15 are mounted on the planer bed 16. The roll 10 is then lifted onto the planer bed 16 by means of a suitable crane and the roll necks 12 placed in the notches of the V blocks. The V blocks are so positioned that the longitudinal axis 18 of the supported roll is parallel to the direction of the movement of the planer bed 16 along the ways 17. After the roll is in position, the indexing unit 23 is placed on the planer bed and the wrench member 30 fitted over wobbler 13. If necessary, the motor 36 may be energized to turn the wrench member 30 so that the wobbler receiving recess 34 will be correctly aligned with the wobbler 13. If desirable, the crane used to lift the roll 10 into position may be used to hold at least the wobbler end of the roll in a slightly elevated position to facilitate fitting the wrench

member 30 onto the wobbler 13. After the indexing unit 23 is in position, the roll and indexing unit may be lowered so that the roll necks 12 fit into the V blocks 14 and 15. When the indexing unit is in position, it may be clamped or fastened in place on the planer bed 16.

Before cutting a groove 21, the bed 16 is moved along the ways 17 to position the tool 19 adjacent one end of the center portion 11. The tool 19 is then adjusted on the support 20, if necessary, so as to be in position to cut a groove 21. The planer bed is then moved along the ways 17 so as to move the roll past the cutting tool. One or a plurality of strokes may be required to cut a groove in the surface of the roll. After a groove has been completed, the motor 36 is energized through suitable control means to turn the gears 38, 39, and 41 and rotate the wrench member 30 and the roll through a few degrees about the longitudinal axis of the roll. By means of the indexing unit 23, the roll 10 is readily and quickly turned to position the roll for the necessary cut. The bed 16 is then again moved along the ways 17 so as to effect relative movement of the tool 19 along the surface of the roll. These steps are repeated until the desired number of grooves have been cut in the roll.

By means of the present apparatus, it is possible to cut the grooves 21 in a blooming mill roll in from $1\frac{1}{4}$ to 3 hours, or less; whereas, when positioning the blooming mill roll with the aid of a crane, as has been the practice, it requires about 8 to 10 hours, or more, to complete cutting of the grooves 21.

35 I claim:

An indexing unit for turning a blooming mill roll about its longitudinal axis to position the roll for cutting a plurality of parallel longitudinal grooves in the roll surface, said roll having an 40 irregularly shaped wobbler on at least one end and said unit comprising, in combination, support means including stationary longitudinally spaced apart plates, a bearing on each plate, said bearings presenting longitudinally spaced apart bearing surfaces each disposed in a plane normal to the longitudinal axis of the roll, a wrench member having a wobbler receiving recess extending longitudinally through the member with the recess being shaped to fit over the wobbler and have the wobbler extend therethrough, a ring gear extending about the external periphery of the wrench member and extending outwardly between the spaced plates, said wrench member 45 having longitudinally extending bearing shoulders disposed on opposite sides of the ring gear and said bearing shoulders being rotatably mounted on said bearing surfaces, gear means including a gear rotatably mounted on and between said plates and meshing with said ring gear, and a drive motor connected to the gear means for actuating the gears and rotating the wrench member and the roll.
